WARP STOP MECHANISM FOR LOOMS.

Application filed November 18, 1924. Serial No. 748,855.

To all whom it may concern:

Be it known that I, CARL D. BROWN, a citizen of the United States, and a resident of Hopedale, in the county of Worcester 5 and State of Massachusetts, have invented an Improvement in Warp Stop Mechanisms for Looms, of which the following description, in connection with the accompanying drawings, is a specification, like characters 10 on the drawings representing like parts.

This invention relates to warp stop mechanism for looms whereby the loom is brought to rest when a warp thread breaks or becomes too slack for weaving purposes.

Mechanisms of this general type comprise 15 a series of drop wires which are normally supported by the warp threads during weaving and when one or more warp threads become too slack for weaving purposes, the supported drop wire moves into the path, 20 of a detector, which is thereby arrested in its detecting movement and through the connected mechanism effects loom stoppage. Owing to the large number of warp threads 25 in the sheet passing from the warp beam, and the inconspicuous character of the drop wires, much difficulty is experienced by the weavers in locating the warp fault, for the purpose of piecing up broken ends or 30 remedying the undue slackness thereof, and one of the objects of the present invention, therefore, is to provide a warp stop mechanism wherein means shall be provided for 35 at once indicating the position of the warp fault whenever the loom is brought to rest through the warp stop mechanism.

In that type of warp stop mechanism where a vibrating detector is employed, it has been usual heretofore to effect loom 40 stoppage whenever a drop wire arrests the detecting movement of the detector through a train of mechanism made effective by the arrest of the detector. Another object of the invention, therefore, is to provide a 45 warp stop mechanism wherein not only shall the warp fault be located automatically, but the loom shall be brought to rest through movement of the detector in a direction other than its detecting directional 50 movement.

In the broader aspects of the present invention, the detector is given a detecting movement and is adapted to be arrested by a drop wire when it fails to be supported by its warp thread, and this arrest of the

detector is utilized in the present invention to impart to the detector another movement in a direction different from its detecting movement, to change the position of the engaged drop wire to locate the warp fault. 50 In accordance with the present invention, also, this additional movement imparted to the detector when it is arrested by a drop wire is utilized to act through a train of stopping mechanism to effect loom stoppage, 55 so that in the present invention, the detector after being stopped by a drop wire, is given another movement for the two-fold purpose of first locating the warp fault by changing the position of the drop wire, and second, 60 to effect loom stoppage.

The above features of the present invention and other novel combination of parts will best be made clear from the following description and the accompanying drawings 75 of one good practical form thereof, it being understood that the invention in its true scope will be definitely set forth in the claims.

In the drawings:

Fig. 1 is a perspective view of a loom containing the present invention, certain parts of the loom mechanism being omitted for 80 clearness of illustration;

Fig. 2 is an enlarged cross-sectional view 85 through the main parts of the warp stop mechanism;

Fig. 3 is a plan view of a portion of the warp stop mechanism showing the train of 90 transmission devices for effecting loom stoppage;

Fig. 4 is a detached detail showing the stopping mechanism as being actuated to stop the loom when the detector is given its 95 stopping movement;

Fig. 5 is an enlarged detail showing the relation of parts which are actuated by the lay to bring the loom to rest on the occurrence of a warp fault; and

Fig. 6 is an enlarged perspective view 100 showing certain details in the train of transmission mechanism between the warp stop motion and the lay actuating devices.

In the drawings the loom frame 1 may be of usual construction suitable to support the 105 operative parts of the loom, and mounted at the front of the loom is the usual shipper 2 which is held in a notch 3 to maintain the loom in operation. Pivotaly mounted on the loom frame and preferably below the 110

breast-beam is a knock-off 4, the end 5 of which bears upon the front side of the shipper 2. The knock-off 4 is pivotally supported at 6 and has connected thereto the rod 7 which extends rearwardly and is joined to a shoe 8 having a slot 9 into which extends the pin 10 secured to the dog or fan-tail 11, which itself is pivotally supported on the rock shaft 12. The fan-tail 11 has a sliding movement on the shaft 12 in addition to its pivotal movement, and such sliding movement is provided by a slot 13, indicated by dotted lines in Fig. 3. The shoe 8 is likewise pivotally supported by a slot connection 14 (Fig. 5) with the shaft 12, the construction being such that should the dog or fan-tail 11 be moved rearwardly, it will act through the pin 10 to move the shoe rearwardly, pull upon the rod 7 and actuate the knock-off 4 to stop the loom.

Secured to the rock shaft 12 is the positioning arm 15, provided with an enlarged slot 16 into which projects a pin 17 extending from the dog or fan-tail 11 (Figs. 3 and 5), the construction being such that if the positioning arm 15 is raised, it will lift the dog or fan-tail 11 and position it in the path of a bunter 18 mounted on the lay 19, so that as the lay moves back, as indicated in Fig. 1, the dog or fan-tail 11 will be struck by the bunter and cause loom stoppage. The details of the mechanism just described may be varied, but the form thereof herein shown is a good practical form of this feature.

The rock shaft 12 is mounted for rocking movement in a bearing 20 which may be conveniently supported by a bracket 21 mounted on the loom frame. The rock shaft 12 is under control of transmission mechanism extending to the warp stop motion, such transmission mechanism being so constructed and arranged that rocking movement may be imparted to the rock shaft 12 to operatively position the dog or fan-tail 11, as described, when the detector is given its stopping movement.

In the present instance of the invention, means has been provided for yieldingly actuating the dog or fan-tail through such mechanism. In the present instance, as indicated in Figs. 3 and 6, the rock shaft 12 has secured thereto the sleeve 22 by means of a set screw 23, and housed within the sleeve 22 is a spring 24, one end of which at 25 is secured to the housing and consequently to the shaft 12, while the other end 26 thereof is connected to the hub 27 of an arm 28 which is mounted loosely upon the shaft 12. Between the housing 24 and the hub 27 are the shoulder portions 29, one on the housing and one on the hub, the construction being such that should the arm 28 be pulled downwardly, (Fig. 1) the hub 27 will be turned against the tension of the spring 24

and will act therethrough to yieldingly move the dog or fan-tail 11 into operative position, and when the arm 28 is raised, the spring 24 will act through the shaft 21 to carry the dog 11 out of operative position. The train of mechanism described is found to be a good practical form of transmission mechanism between the warp stop mechanism and the dog, but within the present invention this train of mechanism may be indefinitely varied.

The arm 28 is connected by a rod 30 to an arm 31 (Fig. 1) mounted for rocking movement upon a stud or dead shaft 32, and a stop finger 33 may be employed above the arm 31 to limit its upward movement.

As indicated in the drawings, Fig. 1, the arm 31 is mounted on the stud or dead shaft 32 by means of a yoke 34 and has a projecting portion or arm 35 which is connected by a rod 36 to a part, presently to be described, for effecting loom stoppage when said part is actuated by the secondary motion of the detector.

Rising from the loom frame are the supports 37, one at each end of the loom, on which the side brackets 38 of the warp stop mechanism are mounted. In the present instance, the brackets 38 are provided with the slotted lug 39 through which extends a bolt 40 for securing the brackets 38 in the desired position at opposite sides of the loom frame.

Between the brackets 38 are the drop wires 41 of the stop motion, which may be arranged in one or more series, and as shown, may be guided in their movements by means of the drop wire guides 42 which, in the present instance, pass through slotted openings 43 in the drop wires 41. As shown, each drop wire is provided with an eye 44 through each of which passes a warp thread *a* (Fig. 2) whereby the drop wires are normally held supported by the intact warp threads. As shown, the warp stop motion proper is provided with the side bars 45 over which the warp threads *a* pass from the warp beam to the shedding mechanism, and at the lower portion of each of the side bars 45 is preferably (though not necessarily) secured a toothed plate 46 against which a drop wire may bear when it engages and arrests movement of the detector.

The particular form of the drop wires and the manner of support by the warp threads may be varied, and any of the usual forms of drop wires may be employed, because the present invention is not circumscribed by this detail, the only essential in this respect being that when a warp thread becomes broken or too slack for weaving purposes that it may move into a position to arrest the detecting movement of the detector.

Mounted in suitable bearings 47 which may be conveniently formed in a down-

wardly extending portion of the brackets 38 at each side of the loom is a detector rock shaft 48 which extends transversely of the loom, as shown, and is capable of endwise movement. Secured to the detector rock shaft 48 is the detector, which in the present instance comprises a toothed bar 49 connected to the rock shaft by means of the arms 50, the hub portions 51 of which are secured to the rock shaft by suitable means such as the bolts or threaded pins 52. The detector bar 49 as shown has teeth 53 at each edge portion thereof, and by this arrangement the detector bar 49 may cooperate with two rows or series of drop wires.

Fixed to and movable with the detector rock shaft 48 is a lug 54 having a cam surface 55. The lug 54 may be secured to the detector shaft 48 in any approved way, but as shown, such connection is effected by a pin 56, Fig. 1.

Loosely mounted to the detector shaft 48 is the cooperating cam member 57 (Fig. 1) having an arm 58 secured to or formed integral therewith, and connected by a rod 59 to an actuator, which may comprise any of the usual means, now well-known, for imparting a rocking movement to the arm 58. The actuator for the arm 58 forms no special part of the present invention and is therefore not hereinafter shown and described, since it is well-known. The hub portion of the member 57 bears against the hub portion of a support or arm 60 which may be conveniently mounted upon one of the warp supporting cross-bars 45, as indicated in Fig. 1.

In accordance with the present invention, the detector shaft 48 is normally under the influence of means for holding the part 57 and cam surface 55 of the lug 54 in operative engagement, so that upon rocking movement of the part 57 through its actuator, as described, the detector shaft will be given its rocking or detecting movement. In the present instance of the invention, the detector shaft 48 is provided with a spring 61 (Fig. 1) one end of said spring resting against the hub portion of the support 60 and the other end of the spring resting against the hub 62 of one of the arms 50 to which the detector bar 49 is secured. This arrangement affords a simple and convenient means for maintaining the detector rock shaft 48 yieldingly pressed in one direction and operating to maintain the cam 55 and part 57 in engagement, but within the true scope of the invention this means and the details thereof may be varied.

From the construction thus far described it will be apparent that during weaving with normally conditioned warp threads, the drop wires will be supported out of the path of movement of the detector bar, but should the warp thread break or become too slack

for weaving purposes, the previously supported drop wire will pass into the path of movement of the detector bar and be caught between the adjacent toothed edge portion of the plate 46 on one of the cross-bars 45 of the warp stop mechanism, and consequently stop the detector. The actuator, acting through the arm 58 of the part 57, however, continues to operate to rock the part 57, with the result that the detector shaft 48 is moved endwise in the direction of the arrow (Fig. 1) against the tension of the spring 61, and carries with it also the detector bar 49, with the result that the engaged drop wire 41, as indicated in Fig. 3, is given a diagonal position between the detector bar and the adjacent cross-bar 45 to thereby indicate the position of the warp fault, as will be apparent from Fig. 1.

As hereinbefore indicated, the present invention utilizes the endwise movement of the detector or detector shaft to effect loom stoppage, and while various forms of mechanism may be employed for this purpose, the following details of such mechanism are found to be a good practical form of this feature.

Mounted adjacent one end of the detector and preferably opposite the end of the detector shaft is a rocker which partakes of its rocking movement by endwise movement of the detector shaft. As shown, the rocker comprises a belt crank lever pivoted at 63 (Fig. 4) on a support 64, which may be adjustably secured to one of the bars 45, constituting the main parts of the warp stop motion. The support 64, as shown, extends upwardly and is provided with a slot 65 by which it may be secured in adjusted position by a bolt 66 (Fig. 2), the construction being such that by manipulation of the bolt 66 the pivotal support of the rocker may be raised or lowered to vary the amplitude of movement effected thereby through the train of transmission mechanism to the dog or fan-tail 11.

The rocker comprises an upstanding portion 67 (Fig. 4) adapted to be engaged by the end 68 of the detector shaft 48 when the latter is moved in the direction of its longitudinal axis. The other arm 69 of the rocker is connected to the rod 36, hereinbefore described, and the rod 36 is joined at 70 (Fig. 1) to the train of transmission mechanism, the construction being such that should the detector shaft 48 be moved longitudinally, it will contact with the upstanding arm 67 of the rocker and through the transmission mechanism place the dog or fan-tail in operative position to be struck by the bunter 18 on the lay as the latter moves back, to thereby stop the loom.

The amplitude of movement of the rocker will of course change the amplitude of movement of the dog or fan-tail and by

proper adjustment of the pivotal support of the rocker through the means described, the amplitude of movement of the dog or fantail may be adjusted to suit any loom to which the warp stop mechanism may be applied.

From the construction described it will be apparent that during the operation of the loom with intact or normally conditioned warp threads, the detector will move through its detecting path without obstruction. Should a drop wire fail to be supported by its warp thread, it will drop into the path of the detecting movement of the detector and be caught between the serrated edge of the detector and the serrated edge of the bar 46 (Fig. 3) to thereby arrest the detector. When the detector is thus arrested and the actuator operating through the arm 58 continues in action, the cam surface of the parts 57 and 54 will have relative movement to move the detector shaft 48 longitudinally in the direction of the arrow (Fig. 1) against the tension of the spring 61, and the connected detector bar 49 will move with it, resulting in changing the position of the drop wire 41 (Fig. 3) so as to indicate the position of the warp fault, and simultaneously with such indication, the detector shaft 48 will act upon the arm 67 of the rocker and effect loom stoppage.

It may sometimes be desirable to provide the rocker arm 31 with resilient means to assist in returning the parts to their normal position after the stopping indication, and to this end the arm 31 may have connected thereto, as indicated in Fig. 3, the spring 71, one end of which may be secured at 72 within the bushing 73 secured to the stud or rock shaft 32. This, however, may not always be necessary, because the weight of the parts will naturally turn them to their inoperative position after the stopping indication of the loom when the shipper is again moved to its running position.

What is claimed is:

1. In a warp stop mechanism for looms, the combination of a series of drop wires, normally supported by the warp threads during weaving, a detector having a detecting movement and adapted to be arrested in that movement by a drop wire, and means rendered effective by the arrest of the detector movement to impart to the detector another movement to indicate the location of the warp fault.

2. In a warp stop mechanism for looms, the combination of a series of drop wires, a detector having a detecting movement in a direction longitudinally of the warp threads, and automatic means for imparting another movement to the detector when its detecting movement is arrested by a drop wire to locate the warp fault.

3. In a warp stop mechanism for looms, the combination of a series of drop wires, a detector having a detecting movement and adapted to be arrested in that movement by a drop wire, and means rendered effective by the arrest of the detector movement to impart to the detector another movement transversely of the loom to indicate the location of the warp fault.

4. In a warp stop mechanism for looms, the combination of a series of drop wires normally supported by the warp threads during weaving, a detector having a detecting movement and adapted to be arrested in that movement by a drop wire, means rendered effective by the arrest of the detector movement to impart to the detector another movement to indicate the location of the warp fault, and means actuated by said other movement of the detector for stopping the loom.

5. In a warp stop mechanism for looms, the combination of a series of drop wires normally supported by the warp threads during weaving, a detector having a detecting movement adapted to be arrested by the drop wire, and means rendered operative by arrest of the detector movement to impart movement to the detector in another direction, and means actuated by movement of the detector in said other direction for effecting loom stoppage.

6. In a warp stop mechanism for looms, the combination of a series of drop wires, a detector having a detecting movement and a loom stopping movement, and means rendered effective for imparting the stopping movement to the detector by arrest of its detecting movement.

7. In a warp stop mechanism for looms, the combination of a series of drop wires, a detector having a detecting movement in one direction and a loom stopping movement in another direction, and means rendered effective for imparting the loom stopping movement to the detector by arrest of its detecting movement.

8. In a warp stop mechanism for looms, the combination of a series of drop wires normally supported by the warp threads during weaving, a detector having a detecting movement adapted to be arrested in that movement by a drop wire, and means made operative by arrest of the detector movement to impart to the detector a stopping movement, and means for stopping the loom when the detector partakes of its stopping movement.

9. In a warp stop mechanism for looms, the combination of a series of drop wires, a detector having a detecting movement which is arrested by a drop wire when it fails to be supported by a warp thread, means rendered effective by arrest of the detecting movement of the detector to impart a move-

- ment of the detector in a direction parallel to the series of drop wires for effecting loom stoppage and changing the position of the drop wire to locate the warp fault.
- 5 10. In a warp stop mechanism for looms, the combination of a series of drop wires, a detector, means for imparting detecting movement to the detector, mechanism actuated through said means for automatically imparting a movement of the detector in a different direction when its detecting movement is arrested by a drop wire to change the position of the engaged drop wire and locate the warp fault.
- 15 11. In a warp stop mechanism for looms, the combination of a series of drop wires, a detector comprising a rock shaft and toothed bar, means for imparting a detecting rocking movement to the rock shaft, and means 20 for automatically moving the rock shaft and toothed bar transversely of the loom when the rock shaft is arrested in its rocking movement by a drop wire to change the position of the drop wire and locate the warp fault.
- 25 12. In a warp stop mechanism for looms, the combination of a series of drop wires, a detector having detecting movement and a loom stopping movement, means for moving the detector to impart the detecting movement and when that movement is arrested by a drop wire to thereupon impart stopping movement to the detector, and means for stopping the loom when the 30 detector is given its stopping movement.
- 35 13. In a warp stop mechanism for looms, the combination of a detector having a toothed bar for engaging a drop wire when it fails to be supported by a warp thread to thereby arrest the detector, and means rendered effective by arrest of the detector movement to automatically move the toothed bar in another direction to change the position of the engaged drop wire to locate the 40 warp fault.
- 45 14. In a warp stop mechanism for looms, the combination of a series of drop wires, a detector comprising a rock shaft and a detector bar secured thereto, means for im- 50 parting a detecting movement to the rock shaft and detector bar which movement is adapted to be arrested by a drop wire when it fails to be supported by a warp thread, and mechanism actuated by said means when the detector bar is arrested to impart another 55 movement thereto and change the position of the drop wire to locate the warp fault.
- 55 15. A warp stop mechanism for looms comprising in combination, a series of drop wires, a rock shaft, a detector bar secured to 60 the rock shaft, means for imparting rocking movement to the rock shaft and detector bar intersecting the vertical plane passed through the series of drop wires and for automatically imparting movement to the 65 detector bar in a direction substantially parallel to said vertical plane when the detecting movement of the bar is arrested by a drop wire for changing the position of the drop wire to locate the warp fault. 70
- 70 16. A warp stop mechanism for looms, comprising, in combination, a series of drop wires, a rock shaft having a detector bar, means for imparting a detecting movement to the detector bar which is adapted to be 75 arrested by a drop wire, automatic means for imparting an endwise movement to the rock shaft when the detecting movement of the detector bar is arrested, and stopping means actuated by endwise movement of the 80 rock shaft for effecting loom stoppage.
- 80 17. A warp stop mechanism for looms, comprising, in combination, a series of drop wires, a rock shaft having a detector bar, means for imparting a detecting movement 85 to the detector bar which is adapted to be arrested by a drop wire, automatic means for imparting an endwise movement to the rock shaft when the detecting movement of the detector bar is arrested, stopping means actuated by endwise movement of the 90 rock shaft for effecting loom stoppage, and means for adjusting the amplitude of movement of the stopping means.
- 90 In testimony whereof, I have signed my name to this specification.

CARL D. BROWN.
